UNITED STATES PATENT OFFICE

161,253

TEAPOT OR THE LIKE

Antony P. Freeman, San Francisco, Calif.

Application September 17, 1948, Serial No. 148,638

Term of patent 14 years

(Cl. D44—25)

To all whom it may concern:

Be it known that I, Antony P. Freeman, a citizen of the United States, residing in the city and county of San Francisco, State of California, have invented a new, original, and ornamental Design for a Teapot or the Like, of which the following is a specification, reference being had to the accompanying drawing, forming a part hereof.

Figures 2 and 3 are perspective views, showing opposite sides thereof.

I claim:

The ornamental design for a teapot or the like substantially as shown.

ANTONY P. FREEMAN.
